WITNESS:

W. O. Critchfield, INVENTOR
BY *Victor J. Evans*

ATTORNEY

UNITED STATES PATENT OFFICE.

WALTER O. CRITCHFIELD, OF SHELBY, OHIO, ASSIGNOR TO SHELBY SALESBOOK COMPANY, OF SHELBY, OHIO.

SALES-BOOK ATTACHMENT.

Application filed March 21, 1927. Serial No. 177,066.

The object of this invention is to provide a salesbook including main and supplemental series of leaves or sheets mounted in separate holders, and a cutting edge or straight edge 5 to be carried by the element mounting the main series of sheets, and adapted to be moved to operative position, where it is employed to facilitate the tearing off of sheets from the supplementary book along a line adjacent to 10 the mounting device for this series.

A further object is to avoid the necessity of employing perforated sheets in the supplemental series or employing a row of stitching especially for the purpose, which involves additional labor and cost, in the production of 15 the books in quantities.

A further object is to provide a straight edge for the purpose indicated, which shall comprise a flat metallic blade or plate having 20 slots at an angle with the cutting edge and adapted to be moved into and out of operative position, in the manner indicated below, the blade being movably mounted by means of pins, rivets or the like.

25 With the foregoing and other objects in view, the invention consists in the novel construction and arrangement of elements described, illustrated and claimed, it being understood that modifications may be made 30 within the scope of the claims without departing from the spirit of the invention.

In the drawings forming part of this application,

35 Figure 1 is a plan view of the salesbook in open position.

Figure 2 is a view showing the rear side of the mounting device for the series of sheets on the right of Figure 1, the blade or plate being illustrated in closed position, whereas, 40 in Figure 1, it is in operative position.

Figure 3 represents a section in a plane indicated by line 3—3 of Figure 2, but shows the metallic plate on the under side of the cover or back, or normal inoperative position.

45 Figure 4 is a perspective view of the cutting device or straight edge, detached.

The main series of leaves or sheets is shown at the right of Figure 1, and is designated 10, this series being mounted in a spring controlled clamp shown more or less conventionally and designated 12. The sheets of this series are to be double sheets, and carbon

sheets are interposed between the leaves designed to carry the written matter.

The package of leaves or sheets designated 10 is mounted on the right hand portion 13 of the cover, this portion being foldable at 13' over the back 14, the opposite element of the cover being designated 15 and adapted to carry a supplemental series of leaves or 60 sheets, as indicated at 16. The sheets of series 16 are for use in conjunction with those of the main series designated 10, and these sheets 16 are retained by a clamp or suitable holding device, a portion of which is shown 65 conventionally and is designated 18. This clamp or sheet holding device 18 may include metallic strips connected by any suitable headed element, no importance being attached to the type of device used for holding sheets 16, except that it may be positioned to prevent accidental movement of element 21. Between the series thus mounted at the left of Figure 1, and the series mounted at the right, is a space, as indicated at 19, and 70 this space is between the flexible edge portion or back of the book 20, and the series of sheets designated 10. The clamping element 18 may be substantially on a line with the edge of portion 14 of the book cover, or the 75 back thereof.

In order to avoid the use of perforated sheets at the left of Figure 1, or of sheets which have been provided with a separate row of stitching, and thereby perforated, I 80 provide a straight edge, plate, or blade, designated 21, and shown in several of the views, but appearing in perspective in Figure 4. This plate or straight edge 21 is provided with slots 22 which extend at an angle with the edge or edges of the plate, and retaining devices of any suitable type, headed on opposite ends, as shown in Figure 3, pass thru the slots 22, and are designated 23.

Sheet mounting device 13 has been described as being foldable at 13', and the fingers of the user may therefore be inserted under the bottom or left edge by raising that edge. The device 21 is readily movable from an inoperative position, behind the element 13 of Figure 1, to an operative position, where it extends across the space 19, and just overlaps the line defined by clamping device 18, so that a straight edge is provided permitting 95 100

of the tearing off of any of the sheets from the pile designated 16, in an obvious manner. A clear cut is thereby provided, and there is no interference at any time with the use of the book by the mounting of the knife or edge 21, as the latter is immediately restored, after use, to inoperative position.

Having described the invention what is claimed is:—

- 10 1. A salesbook, comprising a plurality of cover members flexibly connected, a foldable sheet mounting device secured at its outer edge to one of said cover members, a second sheet mounting device for a supplemental series of sheets, secured to one of the cover members, and a plate providing a straight edge carried

by the foldable sheet mounting device and slidable therefrom toward the series of supplemental sheets.

- 20 2. A salesbook, comprising a plurality of cover members flexibly connected, a foldable sheet mounting device secured at its outer edge to one of said cover members, a second sheet mounting device, for a supplemental series of sheets, secured to the same cover member, a plate having a straight edge, and having slots therein at an angle with said edge, and means passing thru the slots for connecting the plate with the underside of the foldable sheet mounting device.

25 30 In testimony whereof I affix my signature.
WALTER O. CRITCHFIELD.
